UNITED STATES PATENT OFFICE

111,078

DESIGN FOR A COVER FOR A COOKING VESSEL OR SIMILAR ARTICLE

Adrien L. Langel, Chicago, Ill., assignor to Chicago Metallic Manufacturing Company, a corporation of Illinois

Application January 28, 1938, Serial No. 74,679

Term of patent 14 years

To all whom it may concern:

Be it known that I, Adrien L. Langel, a citizen of the United States, residing at Chicago, in the county of Cook and State of Illinois, have invented a new, original, and ornamental Design for a Cover for a Cooking Vessel or Similar Article, of which the following is a specification, reference being had to the accompanying drawing, forming part thereof.

Fig. 1 is a top plan view of the article showing my new design; and

Fig. 2 is a side elevational view thereof.

I claim:

The ornamental design for a cover for a cooking vessel or similar article, substantially as shown.

ADRIEN L. LANGEL.
